UNITED STATES PATENT OFFICE

1,973,894

EXTENSION TABLE

William Andrew Duncan, Statesville, N. C.

Application June 12, 1933, Serial No. 675,497

5 Claims. (Cl. 45—113)

The object of my invention is to provide improved devices for adjusting and supporting leaves of refectory tables adapted to be easily and quickly operated to shift to leaves from a concealed position under the table top to a position in alignment with the surface of the table top to function as an extension of same; to provide apparatus adapted to furnish a strong and secure support for the leaf when it is adjusted to the extension position; and to provide novel means for permitting of easily and quickly adjusting the leaf vertically to permit the operator to bring the top surface of the leaf into perfect alignment with the top surface of the table top. It is also an object of my invention to provide apparatus of this character which can be manufactured at moderate cost and which can be readily attached by manufacturers of refectory tables to such tables without changing the construction of the tables except to provide slots for the slides.

It is also an object of my invention to provide novel means for automatically illustrating the table leaf into a position approximately in alignment with the table top as the leaf is drawn outwardly to its extended position. I attain these and other objects of my invention by the mechanism illustrated in the accompanying drawing in which—

30 Figure 1 is a longitudinal vertical section through a refectory table showing my invention applied thereto;

Fig. 2 is a transverse section through the table on line 2—2 of Fig. 1;

35 Fig. 3 is a vertical section on line 3—3 of Fig. 2, the table top however being omitted; and Fig. 4 is a horizontal section on line 4—4 of Fig. 2.

Like numerals designate like parts in each of the several views.

Referring to the accompanying drawing, there is illustrated a refectory table 1 having end leaves 2 and the usual bridge bars 5 extending transversely of the table top on the under side.

45 I provide wooden slide bars 3 suitably affixed to the leaves 2 near their outer ends and having tapered blocks 6 glued or otherwise secured to or formed integral with the slide bars 3. Slots are provided in bridge bars 5 of sufficient size to receive the major portion of the guide blocks 6 whereby the leaf will automatically be moved to a position in substantial alignment with the surface of the table top when the leaf and the slide bars are moved to their extended position, as shown at the left hand end of Fig. 1. I provide

stop pins 7 affixed to slide bars 3 to limit the inward movement of said bars as shown at the right hand end of Fig. 1 of the drawing.

I provide metal wear plates 8 on the underside of slide bars 3 as shown in Fig. 2.

As shown in Figs. 2 and 3 I provide a metal plate 9 on which is mounted a gear 10 adapted to mesh in the slots 12 of the slotted bars 11, said bars 11 being engaged by the flanges 15 of plate 9 as shown in Figs. 2, 3 and 4. The outer ends of bars 11 are provided with tapered or slanting ends 13 which exert a wedge action against the metal wear plates 8 on slide bars 3 to effect vertical adjustment of the leaves. I provide guide brackets 14 in which the bars 11 are slidably mounted. I provide a spring 16 engaging in apertures 17 in corresponding ends of adjusting bars 11 to exert an outward tension on said bars. I provide a shaft 18 on which gear 10 is mounted and a suitable handle 19 for manually operating this gear and thereby operating the bars 11 which in turn adjust the table leaf by raising or lowering the slide bars 3 with which their tapered ends 13 engage as shown in Fig. 2.

The operation of the invention will be readily understood by referring to Figs. 1 and 2 of the drawing. In the right hand end of Fig. 1 the leaf is shown in its concealed position and in the left hand end of said figure the leaf at the opposite end of the table top is shown in its extended position aligned with the surface of the table top. To move the leaf from its concealed position, shown in the right hand end of Fig. 1, to its extended position shown in the left hand end of Fig. 1, it is only necessary to pull the leaf out and it automatically moves to the position desired. A further slight adjustment of the level of the leaf may be made if desired by swinging the handle 9 and thereby actuating gear 10, adjusting bars 11 and slide bars 3 which carry and are affixed to the leaf and which bars also have metal wear plates to be engaged by the tapered ends 13 of the adjusting bars 11 whereby a wedge action is exerted by the longitudinal movement of the adjusting bars 11.

The slanting or curved surface 4 of blocks 3 engage the slotted portion 5a of the bridge bars 5 and thus raise the slide bars 3 and leaves 2, as the leaf is moved from its concealed to its extended position.

What I claim is:—

1. In an apparatus for adjusting and supporting leaves of refectory tables, the combination of a metal plate adapted to be affixed to the

- bridge bar extending transversely of a refectory table, said plate having opposite reversely bent side portions to function as guide elements, slotted bars slidable in said guide elements of the plate, a gear mounted on the plate and having its teeth meshing with the slotted portions of the aforesaid bars, a spring extending between and affixed to the inner ends of the aforesaid bars, the bars having tapered outer ends adapted to exert a wedge action, slide bars adapted to be affixed to an extensible leaf of the refectory table, metal guard plates attached to the bottom of said slide bars in position to be engaged by the tapered ends of the slotted bars causing a vertical adjustment of the leaf of the table after it has been moved to its extended position, whereby the leaf may be easily moved from a concealed position under the table to an extended position in alignment with the table top. 5
2. In an apparatus for adjusting and supporting leaves of refectory tables, the combination of a metal plate adapted to be affixed to the bridge bar extending transversely of a refectory table, said plate having opposite reversely bent side portions to function as guide elements, slotted bars, U-shaped in cross section, slidable in said guide elements of the plate, a gear mounted on the plate and having its teeth meshing with the slotted portions of the aforesaid bars, a spring extending between and affixed to the inner ends of the aforesaid bars, the bars having tapered outer ends adapted to exert a wedge action, slide bars adapted to be affixed to an extensible leaf of the refectory table, metal guard plates attached to the bottom of said slide bars in position to be engaged by the tapered ends of the slotted bars causing a vertical adjustment of the leaf of the table after it has been moved to its extended position, whereby the leaf may be easily moved from a concealed position under the table to an extended position in alignment with the table top. 10
3. In an apparatus for adjusting and supporting leaves of refectory tables, the combination of a metal plate adapted to be affixed to the bridge bar extending transversely of a refectory table, said plate having opposite reversely bent side portions to function as guide elements, slotted bars, U-shaped in cross section, slidable in said guide elements of the plate, a gear mounted on the plate and having its teeth meshing with the slotted portions of the aforesaid bars, a spring extending between and affixed to the inner ends of the aforesaid bars, the bars having tapered outer ends adapted to exert a wedge action, slide bars adapted to be affixed to an extensible leaf of the refectory table, metal guard plates attached to the bottom of said slide bars in position to be engaged by the tapered ends of the slotted bars causing a vertical adjustment of the leaf of the table after it has been moved to its extended position, whereby the leaf may be easily moved from a concealed position under the table to an extended position in alignment with the table top. 15
4. As a new article of manufacture a locking mechanism for locking the leaves of tables and the like in a predetermined position, consisting of a metal plate having opposite inturned flanges to function as guide elements, slotted bars slidably mounted in said plate, a gear mounted on said plate and meshing with each of the slotted bars to operate same in a reverse direction when the gear is operated, the bars having tapered ends adapted to function as wedge or locking elements to engage other elements to be locked in a predetermined position. 20
5. In combination with the device defined in claim 4, a spring extending between and connected to corresponding ends of the respective bars and tending to exert an outward pressure or tension on said bars. 25
